UNITED STATES PATENT OFFICE.

CHARLES L. BOND, OF BOSTON, MASSACHUSETTS, ASSIGNOR TO PERCY E. GINN, OF JAMAICA PLAIN, MASSACHUSETTS.

MACHINE FOR FILLING CONTAINERS.

Application filed August 4, 1921. Serial No. 489,693.

To all whom it may concern:

Be it known that I, CHARLES L. BOND, a citizen of the United States, and resident of Boston, county of Suffolk, State of Massachusetts, have invented an Improvement in Machines for Filling Containers, of which the following description, in connection with the accompanying drawing, is a specification, like characters on the drawing representing like parts.

This invention relates to machines for filling containers with material in a powder or granular form, and it has for its objects to provide a novel machine of this type in which the container to be filled is supported on a vertically movable platform, and in which the filling mechanism comprises a delivery spout adapted to enter the empty container so that as the material is delivered to the container, the latter and the platform will be forced downwardly, and in which means are provided for automatically stopping the filling mechanism from operation when the platform has been depressed to a predetermined point.

A further object of the invention is to provide a machine of this type which is constructed to present more or less resistance to the downward movement of the platform, and whereby the material will be delivered to the container under a greater or less pressure. With this construction the material may be packed into the container under a considerable pressure, or may be delivered to the container under a light pressure, depending upon the character of the material.

A further object of the invention is to provide a device of this type which is so sensitive that it can be used either as a weighing machine to deliver a predetermined weight to each container, or as a filling machine which delivers a predetermined volume to each container.

A further object of the invention is to provide a machine of this type which is simple in its construction and is easily operated, but which is at the same time positive in its operation.

Further objects of the invention are to improve generally machines of this type, all as will be more fully hereinafter set forth.

In order to give an understanding of my

invention, I have illustrated in the drawings a selected embodiment thereof, which will now be described, after which the novel features will be pointed out in the appended claims.

In the drawings, Fig. 1 is a front view of a machine embodying my invention.

Fig. 2 is an enlarged vertical sectional view through the hopper and discharge spout.

Fig. 3 is a detailed view of the releasing means for the clutch.

Fig. 4 is an enlarged section on the line 4—4 Fig. 1.

Fig. 5 is a fragmentary perspective view of the circuit-closing device.

My improved machine comprises a vertically movable platform on which the container to be filled is supported, a filling mechanism having a discharge spout adapted to enter the container so that as the material is delivered to the container, the latter and the platform will be forced downwardly, means for positively delivering the material through the discharge spout, and means for stopping the operation of the delivery mechanism when the platform has been depressed to a predetermined point.

The operative parts of the machine are sustained on a suitable frame, which is herein shown as comprising uprights 1, rising from a base 2, and suitably connected together by cross members 3 and 4.

The platform on which the container to be filled is supported is shown at 5, and it is illustrated as being carried by a vertically movable rod 6, which in turn is pivotally sustained on two parallel arms 7 and 8, that are pivoted to one of the uprights at 9 and 10 respectively. With this arrangement, the platform 5 can have a vertical movement, but will always be maintained in horizontal position.

The arm 8 is shown as provided with a counter weight 11, which can be adjusted thereon and which serves to balance the weight of the platform and rod 6.

The container to be filled is indicated by dotted lines at 12 in Fig. 1, and it may be in the form of a bottle or a carton or a can, or may have any other shape or construction. The carton is filled from a filling

mechanism, which comprises a hopper 13, herein shown as carried by the cross members 3 and 4, and which is adapted to receive the material to be filled, said hopper 5 having an opening 14 in its top, through which the material may be introduced. Said filling mechanism also comprises a discharge spout 15 at the lower end of the hopper, and through which the material is delivered 10 to the container 12, and means for positively feeding the material through the discharge spout. The discharge spout 15 is of a size adapted to enter the container, and it is so constructed that when an empty container is 15 placed on the platform, and the latter is raised, the discharge spout will enter the container and the delivery end of the discharge spout will be adjacent to the bottom of the container, as shown clearly in Fig. 1.

20 For feeding the material through the discharge spout positively, I prefer to use a feed screw 16, as said screw will function not only to feed the material when it is rotated but will also act as a valve to prevent the material from being discharged when said feed screw is idle. This feed screw is carried by a shaft or spindle 17, and is given its rotation by means of a bevel gear 18, which meshes with another bevel gear 19, carried on a driving shaft, sustained in suitable bearings 20 mounted on a frame. The driving shaft has a driving pulley 21 thereon, by which it is driven, and this pulley may be operated from any suitable 35 source of power.

I have herein shown a motor 22 for operating the shaft, the latter being belted to the pulley by the driving belt 23. The belt pulley 21 is shown as connected to the 40 shaft through the medium of a clutch 24, which may be of any suitable construction, and which is herein shown as operated by a clutch actuator 25, pivoted to the frame at 26, and having a forked arm 27, which operates in a groove in a sliding collar 28. The clutch is constructed so that the movement of the collar 28 toward the right Fig. 1 will throw the clutch into engagement, and movement in the opposite direction will 45 disengage the clutch. The clutch actuator is shown as being acted on by a spring 29, which normally tends to disengage the clutch.

50 Means are provided for throwing the clutch into engagement when the platform 5 is raised, and for holding said clutch in engagement during the descending movement of the platform and until the latter reaches a predetermined point, at which time said means becomes inoperative and the clutch is disengaged automatically by the spring 29. Therefore, when an empty container is placed on the platform 5, and the latter is raised into the position shown 55 in Fig. 1 to cause the delivery spout to enter

said container, the clutch will be thrown into engagement, thereby rotating the feed screw 16, and said clutch will be held in engagement as the platform 5 with the container descends, until the container has 70 been filled to the desired point, at which time the clutch is automatically released.

To accomplish this end, I have provided a rod or connection 30, which is pivotally connected at one end to the clutch actuator 25, and at the other end it is pivotally connected to an elbow lever 31, which in turn is pivoted to the frame at 32. One arm of this elbow lever is pivoted at 33 to one member 34 of a toggle device 34-35. The toggle member 35 is pivoted at 37.

When the toggle device is straightened, as shown in full lines Fig. 1, the clutch will be thrown into engagement through the connections 30-31, and because of its toggle construction said toggle device, when straightened, acts as a lock to hold the clutch in engagement. When the toggle device is broken, then the spring 29 acts automatically to disengage the clutch.

90 Means are provided whereby the upward movement of the rod 6 necessary to carry an empty container into filling position, will operate to straighten the toggle and thereby throw the clutch into engagement. This is accomplished by providing the rod 6 with a collar 38, which is adapted to engage the toggle device as the rod rises, and thereby straighten it.

Means are also provided for locking the toggle device in its straightened position while the package is being filled and until the platform has been depressed to a predetermined point. The means I have herein provided for this purpose comprise a latch 39 pivoted to an extension 40, formed on the toggle member 35, and adapted to engage a shoulder 41 when the toggle is straightened. So long as the latch is in engagement with the shoulder, the toggle member 35 100 will be locked from movement. This shoulder 41 is formed on a rocking member 42, which is mounted to turn about a pin or shaft 43, and said member has rigid therewith an arm 44, which is adapted to engage 105 a second latch 45, pivoted to the frame at 46. This latch 45 is connected by a link 47 to the armature 48 of a magnet 49. So long as the magnet is deenergized, the armature 48 will be in its lowered position, and the 110 latch 45 will thus be operative to hold the arm 44 in the position shown in Fig. 3, and thus the shoulder 41 will in turn be operative to maintain the toggle device 34-35 straightened.

115 When the platform 5 has been lowered to a predetermined point, the magnet 49 is energized, thus raising the armature 48 and releasing the latch 45 from the arm 44. This will allow the rocking member 42 to turn 120

into the dotted line position, thus releasing the latch 39 and allowing the toggle 34-35 to break into the dotted line position. This permits the spring 29 to function to disengage the clutch.

The magnet 49 is in a normally open circuit, which becomes closed automatically when the platform has been depressed to a predetermined point. This circuit is shown 10 as energized by the battery 63, which is connected to the magnet through two circuit connections 50 and 51, the connection 51 having therein a switch which is normally open, but which is closed when the platform 15 is depressed to the predetermined point. This switch comprises a contact member 52, which is secured to but insulated from the frame 1, and which is connected to the magnet by the wire 53. The switch also includes 20 a contact arm 54, pivoted to a bracket 55, that is carried by but insulated from the frame, said arm normally resting on a pin 56 of insulating material which is carried by a bracket 57, secured to the rod 6. This 25 bracket 57 is adjustably mounted on the rod 6, so that its position thereon can be varied. It will be so adjusted that when the platform is in its lifted position shown in Fig. 1, the contact arm 54 will be held some distance 30 above the contact 52 and the circuit, therefore, will be open. The adjustment of the bracket 57 will be such, however, that when the platform 5 has been depressed to the predetermined point at which the container 35 is filled sufficiently, the contact arm 54 will be brought into engagement with the contact 52, as shown in dotted lines Fig. 1, and when this occurs the circuit through the magnet 49 will be closed and the latter will 40 become operative to trip the latches 39 and 45. This will allow the toggle device to break, thus permitting the spring 29 to disengage the clutch.

The circuit for the magnet 49 also includes, 45 two contact members 58-59, which are secured to but insulated from the frame, and an arm or switch member 60, carried by but insulated from the toggle member 34, and adapted to enter between said contacts, 50 thereby to close the circuit at this point. The purpose of this construction is to provide for opening the circuit as soon as the clutch has been disengaged. When the platform 5 is elevated, and the toggle device 34-35 is 55 straightened, the contact 60 will be entered between the contact 58-59, thus closing the circuit at this point, but such elevating movement of the platform will raise the contact arm 54 off from the contact 52, thus 60 opening the circuit between said contacts. The circuit will remain open until the rod 6 has been depressed to such a point that the contact arm 54 will rest on or engage the contact 52, at which time the circuit is 65 closed, thereby releasing the latch 39, and

said circuit will remain closed until the toggle 34-35 breaks and opens the circuit between the contacts 58-59.

The delivery spout 15 is detachably secured to the hopper, so that feed spouts of different sizes may be used, according to the size of the container. The connection between the feed screw 16 and the gear 18 is also a detachable one, thus permitting the use of feed screws of different sizes to correspond to the size of the delivery spout. The gear 18 is shown as carried by a shaft section 61, to which the feed screw spindle is detachably secured, as shown in 62.

Situated within the hopper are one or more stirrers or agitators, which have for their purpose to maintain the material in the hopper in a loose, free-flowing condition. These stirrers are mounted on a sleeve 63, through which the shaft section 61 extends, 85 and which is rotatably mounted in suitable bearing 64 carried by the hopper. Said stirrers are indicated at 65, 66 and 67 respectively. The sleeve 63 is driven from the gear 18 by means of reducing gearing, so that the rotation of the stirrers is relatively slow compared to that of the feed screw. The said sleeve 63 has fast thereon a gear 68, which meshes with a small gear 69, rotatable about a stud 70. The small gear 69 has rigid therewith a larger gear 71, which meshes with and is driven by a small gear 72, rigid with the gear 18.

The operation of the device is as follows: When the machine is at rest, the platform 100 toggle device 34-35 will be broken and the clutch will be disengaged. The operator takes an empty container and places it on the platform 5, and then raises the platform with the container thereon into the 105 position shown in Fig. 1, so that the delivery spout 15 will enter the container. The final upward movement of the platform will straighten the toggle device 34-35, and thus throw the clutch 24 into 110 engagement, thus setting the feed screw 16 in operation to fill the container. This straightening movement of the toggle device 34-35 also closes the circuit between the contacts 58-59. As the material is delivered to the container by the feed screw, 115 said container and platform will be forced downward, and when they have reached such a position that the contact arm 54 is brought against the contact 52, the circuit 120 will be closed through the magnet, thus tripping the latch 39 and allowing the clutch 24 to be disengaged.

73 is a brake device constructed to apply a retarding or braking action on the drive 125 shaft when the clutch is disengaged, the purpose of this being to bring the feed screw to rest as soon as the clutch is disengaged.

The degree of firmness with which the 130

material is packed into the container will depend upon the resistance which is offered to the downward movement of the platform, and this can be varied by adjusting the counter weight 11. If the counter weight is adjusted to the left Fig. 1, it will offer a greater resistance to the downward movement of the platform, while if it is adjusted to the right it will offer a less resistance. 10 My invention, therefore, provides a means whereby the material may be packed into the container with a greater or less degree of firmness, as desired.

The herein described device can be used 15 equally well for delivering predetermined volumes or predetermined weights. The foregoing describes the operation when the machine is operating to deliver predetermined volumes to the container. In order 20 to deliver predetermined weights the device may be adjusted so that when the platform 5 is fully elevated the delivery spout 15 will not enter the container to any great extent, and the counterweight 11 will be adjusted 25 so that it will be just overbalanced by the desired weight in the container. When used in this way material will be delivered to the container as above described till the weight 30 of the container and the material therein overbalance the counterweight 11; at which time the platform will descend thus closing the circuit at the contacts 52, 54, and causing the clutch to be disengaged. The manner 35 of mounting the platform 5 on the arms 7, 8 makes a very sensitive weighing device which is practically free from friction and which is accurate in operation.

It will be noted that the circuit 50, 51 is arranged to be opened at two points and 40 also that after the circuit has been closed it will first be opened between the contacts, 58, 59. The advantage of this construction is that any arcing which will be created 45 by the breaking of the circuit when the container is filled will occur between the contacts 58, 59, 60 and not between the contacts 54, 52. Consequently the latter contacts will not be subjected to the destructive 50 action resulting from arcing and said contacts will always remain in condition to make a good electrical contact when they are brought together.

Another advantage of this construction is that when the container is filled and the 55 platform 5 is depressed the circuit will be broken thus deenergizing the magnet 49 even though the contacts 54 and 52 remain in engagement.

While I have illustrated a selected embodiment of my invention I do not wish to be limited to the constructional features shown.

I claim:

1. In a machine for filling containers, the 65 combination with a vertically-movable plat-

form to receive the container to be filled, of means to deliver material to said container, said container and platform being depressed as the container fills, means including a clutch to operate the delivery mechanism, a device for holding the clutch in operation, a magnet for releasing said device, a circuit for the magnet arranged to be closed at two places, and means to close the circuit at one place when the platform is raised to bring the container into filling position and at the other place when the platform is lowered to a predetermined point. 70 75

2. In a machine of the class described, the combination with a vertically-movable 80 platform to receive the container to be filled, of delivery means to deliver material to the container, a clutch to actuate said delivery means, a clutch-controlling mechanism rendered operative when the platform is raised 85 to throw the clutch in engagement and hold it in engagement, a magnet to release the clutch-controlling device, a circuit for the magnet arranged to be closed at two different places, means to close the circuit at one 90 place when the platform is raised and at another place when the platform is lowered to a predetermined point.

3. In a machine for filling containers, the combination with a vertically movable platform to receive the container to be filled, of a delivery spout adapted to enter an empty container situated on the platform, means to deliver material into the container through said spout, said container and platform being moved downwardly as the container fills, means including a clutch to operate the delivery mechanism, a latch device to hold the clutch in engagement, electrical- 95 ly-actuated means to trip the latch when the platform has been lowered to a predetermined point and including a circuit arranged to be closed at two places with means to close the circuit at one place when the platform is raised to bring the container into filling position and at the other place when the platform is lowered to a predetermined point, and automatically-operative 100 means to disengage the clutch when the latch is tripped. 105 110

4. In a machine of the class described, the combination with a vertically-movable platform to receive the container to be filled, of delivery means to deliver material to said container, a clutch to actuate said delivery 115 means, a clutch-controlling device operating normally to disengage the clutch, a latch to hold the clutch-controlling device in a position to maintain the clutch in engagement, a magnet to release the latch, a circuit for 120 the magnet arranged to be closed at two places, means to close the circuit at one place when the platform is raised to bring the container into filling position and to close said circuit at the other place when 125 130

the platform is lowered to a predetermined point, whereby the latch will be released and the clutch automatically disengaged.

5. In a machine of the class described, the combination with a vertically-movable platform to receive the container to be filled, of delivery means to deliver material to said container, a clutch to actuate said delivery means, a clutch-controlling device operating normally to disengage the clutch, a latch to hold the clutch-controlling device in a position to maintain the clutch in engagement, a magnet to release the latch, a circuit for the magnet arranged to be closed at two places, means to close the circuit at one place when the platform is raised to bring the container into filling position and to close said circuit at the other place when the platform is lowered to a predetermined point, whereby the latch will be released and the clutch automatically disengaged, the movement of the clutch-controlling device for disengaging the clutch operating to open the circuit at the first-named place.
6. In a machine of the class described, the combination with a vertically movable container-receiving platform, of a delivery spout, means to deliver material through said spout into a container situated on the platform, means including a clutch to operate said delivery mechanism, a latch to hold the clutch in operation, electrically-actuated means to release the latch when the platform has been lowered to predetermined position by the filling of the container, said means including a circuit which is arranged to be opened at two places and means to disengage the clutch when the latch is released.
7. In a machine for filling containers, the combination with a vertically-movable platform to receive the container to be filled, of means to deliver material to said container, said container and platform being depressed as the container fills, means including a clutch to operate the delivery mechanism, a device for holding the clutch in operation, a magnet for releasing said device, a circuit for the magnet arranged to be closed at two places, and means to close the circuit at one place when the platform is raised to bring the container into filling position and at the other place when the platform is lowered to a predetermined point, said means operating to open the circuit at the first-named place when the clutch is disengaged.
8. In a machine of the class described, the combination with a vertically movable platform to receive the container to be filled, of a delivery spout to deliver material to said container, feeding mechanism to feed material through said spout, a clutch to operate said feeding mechanism, means to throw the clutch into engagement when the platform
- is raised, a latch device to hold the clutch in engagement, electrically-actuated means to trip the latch when the platform has been lowered to a predetermined point, said means including a circuit which is opened and closed at two places and means to close the circuit at one place when the platform is raised and at the other place when the platform is lowered to said predetermined point and automatically-operative means to disengage the clutch when the latch is tripped.
9. In a machine of the class described, the combination with a vertically movable platform to receive the container to be filled, of means to deliver material to said container, said container and platform being lowered as the container fills, a clutch to operate the delivery mechanism, a latch to hold the clutch in engagement, a magnet to release the latch, a circuit for the magnet arranged to be closed at two places, means to close the circuit at one place when the platform is raised and to close the circuit at the other place when the platform has been depressed to a predetermined point whereby the latch will be tripped and the clutch disengaged.
10. In a machine of the class described, the combination with a vertically movable platform to receive the container to be filled, of delivery means to deliver material to said container, a clutch to actuate the said delivery means, a latch to hold the clutch in engagement, a magnet to release the latch, a circuit for the magnet arranged to be closed at two points, means to close the circuit at one point when the platform is raised to bring the container into filling position, and means to close said circuit at the other point when the platform is lowered to a predetermined point whereby the clutch will be disengaged.
11. In a machine of the class described, the combination with a vertically movable platform to receive the container to be filled, of delivery means to deliver material to the container, a clutch to operate said delivery means, a toggle device, connections between said toggle device and clutch whereby the clutch will be thrown into engagement when the toggle device is straightened, means to straighten the toggle device by the upward movement of the platform to bring the container into filling position, a latch to hold the toggle device straightened, and means to trip said latch when the platform is lowered to a predetermined point by the filled container.
12. In a machine of the class described, the combination with a vertically movable platform to receive the container to be filled, of delivery means to deliver material to said container, a clutch to operate said

6

delivery means, a toggle device, connections between said toggle device and clutch whereby the clutch is thrown into engagement when the toggle device is straightened, a latch to hold such toggle device straightened, a magnet to trip the latch, a circuit for the magnet arranged to be closed at two points, means to close the circuit at one point when the toggle is straightened, 10 means to straighten the toggle by the movement of the platform necessary to bring the container into filling position, and means to close the circuit at the other point when the platform has been lowered to a predetermined point.

13. In a machine of the class described, the combination with a vertically-movable platform to receive the container to be filled, of delivery means to deliver material 20 to said container, a clutch to operate said delivery means, a toggle device, connections between said toggle device and clutch whereby the clutch is thrown into engagement when the toggle device is straightened, a latch to hold such toggle device straightened, a magnet to trip the latch, a circuit for the magnet arranged to be closed at two points, means to close the circuit at one point when the toggle is straightened, 25 means to straighten the toggle by the movement of the platform necessary to bring the container into filling position, and means to close the circuit at the other point when the platform has been lowered to a predetermined point.

mined point, whereby the magnet trips the latch and the toggle is broken, the breaking of the toggle opening the circuit at the first-named point.

14. In a machine of the class described, the combination with a vertically-movable platform to receive the container to be filled, of delivery means to deliver material to said container, a clutch to operate said delivery means, a toggle device, connections between said toggle device and clutch whereby the clutch is thrown into engagement when the toggle is straightened and is thrown out of engagement when the toggle is broken, automatically-operative means tending to break the toggle device, a latch 40 to hold the toggle device straightened, a magnet to trip the latch, a circuit for the magnet arranged to be closed at two places, means to close the circuit at one place when the toggle is straightened, means to 45 straighten the toggle by the movement of the platform necessary to bring the container into filling position, and means to close the circuit at the other place when the platform has been lowered to a predetermined extent, whereby the magnet trips the latch and allows the toggle device to break and the clutch to be disengaged, the breaking of the toggle device opening the circuit at the first-named point.

In testimony whereof, I have signed my name to this specification.

CHARLES L. BOND.
